England

Application October 11, 1938, Serial No. 234,499
In Great Britain October 16, 1937

4 Claims. (Cl. 158—115)

This invention relates to gas burners and more particularly to gas burners provided with ignition means.

It is known to provide boiling rings or like burners for gas cookers with igniting means for the gas issuing from the burners, but such igniting means are liable to become fouled and put out of action in the event of a pot boiling over which is being heated by the burner. As it is frequently intended that such igniting means should serve to relight the burner in the event of its becoming accidentally extinguished, it is necessary to protect the igniting means by housing the same within a protective casing. If the igniting means are housed within a protective casing mounted on the mixing tube of the burner, the structure of the burner is complicated and the cost of manufacture is excessive, especially when a number of burners are provided, as in the case of a gas cooker.

One object of the present invention is to provide a gas burner arrangement in which standard types of boiling rings and other burners can be employed without being encumbered with igniting means for the burners, and in which each burner is provided with lighting means, including a pilot jet which is in action all the time gas is being supplied to the burner, so as to relight the latter in the event of its becoming accidentally extinguished, but which can be turned off, without interfering with the pilot jet of any other burner which may be in use, when the gas supply to the associated burner is shut off, thereby avoiding waste of gas.

Another object of the invention is to enable the length of the pilot flame to be maintained to the extent necessary to permit the pilot flame to relight the burner, even when the latter is operating with a reduced gas supply.

A further object of the invention is to provide means for shutting off the gas supply to the burner and to the pilot jet in the event of the pilot flame becoming accidentally extinguished.

The invention is illustrated diagrammatically by way of example in the drawing annexed hereto.

Fig. 1 is a plan view of the arrangement in its simplest form, comprising a pair of gas burners.

Fig. 2 is a plan view, and Fig. 3 a corresponding front view of a detail.

Fig. 4 is a vertical section through a further detail, and

Figs. 5 and 6 are horizontal sections on the lines 5—5 and 6—6 of Fig. 4.

Referring to Fig. 1, the main burners *a*, *b*

are each provided with a pilot burner *e*, *f*, respectively, and are supplied with gas under the control of manually actuated gas taps *c*, *d*, one for each main burner, said pilot burners being arranged in proximity to one another to form a unit separate from the main burners and being directed so as to project igniting flames towards the main burners *a*, *b*. The pilot burners *e*, *f* are supported on a platform *q* which is fixed to a bar *p* extending between the burners *a*, *b* and is supported at its ends on the gas cooker in any convenient manner. Gas is supplied to the pilot burners by means of separate pipes *e*¹ and *f*¹ connected up to the respective gas taps *c*, *d* and extending for a part of their length along the bar *p*.

Since the pilot burners are arranged at a distance from the main burners, provision must be made for enabling the pilot flames to be maintained at their maximum length so as to be able to relight the associated main burners in the event of the latter being extinguished, irrespectively whether the gas taps of the main burners are in the full open position or turned down. For this purpose, each gas tap is provided with a separate conduit, comprising a circumferential groove *y*, as shown in Figs. 4 and 6, of such a length that a full supply of gas is admitted to the pilot burner, notwithstanding the position of the tap, as long as any gas is being supplied through the tap to the main burner.

The pilot burners are provided with individual lighting devices, comprising friction wheels *g* rotatably mounted on the platform *q* in proximity to the respective pilot burners and provided with crank arms *m* which are connected by means of rods *o* to crank arms fixed to the gas taps, so that when the gas taps are turned, the rods *o* are reciprocated and turn the friction wheels, which have a roughened surface co-operating with flints *h* mounted in sockets *i*, thereby producing sparks for lighting the gas issuing from the pilot burners *e*, *f*. In order to facilitate the renewal of the flints, the sockets *i* are provided with bores open at both ends and the flints are pressed against the abrasive surfaces of the friction wheels by means of springs *k* bearing against abutments *l* on the platform and acting on levers *j* having projections which take into the bores in the sockets *i* and bear against the ends of the flints *h* therein; the levers *j* can be raised sufficiently to allow the flints to be inserted in the bores in the sockets *i*.

It is desirable to provide means for shutting off the gas supply to the individual pilot burners and their associated main burners in the event

of the pilot flames becoming accidentally extinguished. For this purpose, the movement of the gas tap into the open position is opposed by a coil spring x , one end of which is fixed to the platform q and the other end to the lever m , in such a manner as to turn it and urge the gas tap through the rod o and the lever n into the closed position. The gas tap is maintained in the open position by means of a catch comprising a lever s pivoted at t on the platform q and provided with a tooth s^2 , said lever being under the control of a thermostat device heated by the pilot flame, which maintains the catch in action during the time the pilot flame is alight and prevents the spring x from turning the lever m .

The thermostat device comprises a bimetallic strip in the form of a coil r fixed at one end on a bracket r^1 mounted on the platform q , the said coil having an arm r^2 which engages a notch in the end of the lever s . When the thermostat coil r is heated by the flame of the pilot burner v , the arm moves clockwise and urges the lever s towards a retaining element consisting of a disc s^1 which is rigid with the lever m until the tooth s^2 engages a notch in the periphery of said disc, so as to hold the lever m in the position corresponding to the open position of the gas tap. On the coil r cooling owing to the pilot flame being extinguished, the arm r^2 turns counter-clockwise and releases the tooth s^2 from the notch in the periphery of the disc s^1 , thereby allowing the spring x to turn the lever m and move the gas tap into the closed position. The advantage of a bimetallic strip in the form of a coil is that it is possible to obtain a considerable angular displacement of the free end of the coil, avoiding the necessity of multiplying gear and enabling the free end of the coil in the form of an arm r^2 to engage the lever s directly.

In order to enable the gas supply to the main burner to be reduced or the gas tap c to be turned by hand into the closed position without interfering with the thermostat device and the parts co-operating therewith, by means of the handle c^1 , the lever n is loosely rotatable with respect to the plug of the tap c and operates it through a lost motion device, comprising a dog or the like z on the lever which engages a corresponding dog z^1 on the plug, the arrangement being such that the tap can be turned through 90° relatively to the lever n by means of the handle c^1 . By this means the plug can be turned into the open position by hand and, after the tooth s^2 has moved into engagement with the notch in the periphery of the disc s^1 , the plug can be turned by means of the handle c^1 into the partly or fully closed position without turning the lever n .

If the pilot burner flame is allowed to play continuously upon the coil r , there is the danger of the bimetallic strip becoming permanently stretched or damaged, and in order to prevent this, means are provided for directing the pilot flame away from the coil after the catch has come into action, for instance towards a member in conductive relationship with the coil. As shown in Figs. 2 and 3, the pilot burner v is pivoted at w on the platform q , a pin u provided on the tail of the lever s bearing against the side of the burner v so that in the position shown, the pilot flame is directed away from the coil r towards the bracket r^1 . On the lever s being moved to withdraw the tooth s^2 from the notch in the disc s^1 , the pin u allows the burner v to move into a position in which it can direct the pilot flame against the coil r on the pilot burner being relighted. The

burner v may be moved into this position by means of a spring (not shown) or the pin may engage a slotted lug rigid with the burner v . The burner v forms a mixing tube, the gas being supplied thereto by means of a fixed tube v^1 .

The supporting platform q , together with the igniting devices thereon comprising the friction wheels g , the sockets i housing the flints and the springs k and levers j forms a unit independent of the main gas burners a, b and can be removed from the bar p without interfering with the said burners. The operating rods o may also be removed with the platform q after being released from the levers n . The various elements of the thermostat control device shown in Figs. 2 and 3 being also mounted on the platform q can also be removed therewith as a unit without interfering with the burners a, b .

I claim:

- 20 1. A gas burner arrangement comprising in combination a plurality of main burners, pilot burners, one for each main burner, arranged in proximity to one another to form a unit separate from the main burners and directed so as to project igniting flames towards the associated main burners, manually actuated taps, one for each main burner, for controlling the gas supply to each burner independently, a gas supply pipe for each pilot burner connected up to the tap of the associated main burner, said tap including a rotatable plug portion having a separate groove for controlling the gas supply to the pilot burner capable of admitting a full supply of gas to the pilot burner to maintain the pilot flame at its maximum length at any degree of opening of the tap, and individual lighting devices for said pilot burners located in proximity thereto and operatively connected to the gas taps for igniting the gas issuing from the pilot burners on the respective gas taps being actuated.
- 25 2. A gas burner arrangement, comprising in combination a plurality of main burners, pilot burners, one for each main burner, arranged in proximity to one another and directed so as to project igniting flames towards the associated main burners, supporting means for said pilot burners, manually actuated taps, one for each main burner, for controlling the gas supply to each burner individually, a gas supply pipe for each pilot burner connected up to the tap of the associated main burner, said tap including a rotatable plug portion having a separate groove for controlling the gas supply to the pilot burner and capable of admitting a full supply of gas to the pilot burner to maintain the pilot flame at its maximum length at any degree of opening of the tap, individual igniting devices for said pilot burners mounted on said supporting means, said supporting means together with the igniting devices thereon forming a unit independent of the main gas burners and capable of removal without interfering with the main burners, and actuating means for the ignition devices operatively connected to the individual ignition devices and the respective gas taps for actuating the ignition devices on the gas taps being turned on.
- 30 3. A gas burner arrangement, comprising in combination, a plurality of main burners, a supporting platform arranged between and separate from said main burners, pilot burners, one for each main burner, arranged in proximity to one another above said supporting platform and directed so as to project igniting flames towards the associated main burners, manually actuated taps, one for each main burner, for controlling

the gas supply to each burner independently, a gas supply conduit for each pilot burner connected up to the tap of the associated main burner, ignition devices mounted on said platform, one for each pilot burner, including a rotary friction wheel arranged in proximity to each pilot burner and a spark producing element arranged to co-operate with said friction wheel, actuating means for said friction wheels operatively connected to the respective gas taps so as to turn in unison with the taps, a closing spring operatively connected to each of the gas taps and arranged to urge the tap into the closed position, thermostat devices arranged on the platform in the heating zones of the respective pilot burners, retaining elements fast with the friction wheels and movable catch elements on the platform operatively connected to the respective thermostat devices and arranged to engage said retaining elements in the position thereof corresponding to the full open position of the associated gas taps, so as to maintain the taps in said full open position against the action of the closing springs, said platform, together with the elements mounted thereon being removable without interfering with the main burners.

4. A gas burner arrangement, comprising in combination, a plurality of main burners, a supporting platform arranged between and separate from said main burners, pilot burners, one for each main burner, arranged in proximity to one another above said supporting platform and directed so as to project igniting flames towards

the associated main burners, manually actuated taps, one for each main burner, for controlling the gas supply to each burner independently, a gas supply conduit for each pilot burner connected up to the tap of the associated main burner, ignition devices mounted on said platform, one for each pilot burner, including a rotary friction wheel arranged in proximity to each pilot burner and a spark producing element arranged to co-operate with said friction wheel, actuating means connected to the friction wheels and the respective gas taps to enable the taps and their associated friction wheels to be turned in unison, coil springs having one end fixed to the platform and the other end connected to the respective friction wheels so as to turn the latter to urge the associated gas tap into the closed position, a plurality of thermostat devices arranged on the platform in the heating zones of the respective pilot burners, each of said friction wheels having a retaining member with a notch therein, and a movable catch member on the platform operatively connected to each of said thermostat devices and arranged to co-operate with said notch in the position of the friction wheel corresponding to the full open position of the respective gas tap, so as to maintain the gas tap in the full open position against the action of said coil spring, said platform, together with the elements mounted thereon, being removable without interfering with the main burner.
